Charles Turner Brown,
ATTORNEY.

UNITED STATES PATENT OFFICE.

WILLIAM H. APPLEBY, OF CHICAGO, ILLINOIS.

LATCH.

1,069,753.

Specification of Letters Patent.

Patented Aug. 12, 1913.

Application filed June 17, 1912. Serial No. 704,070.

To all whom it may concern:

Be it known that I, WILLIAM H. APPLEBY, a subject of the King of Great Britain, and a resident of Chicago, in the county of Cook 5 and State of Illinois, have invented certain new and useful Improvements in Latches, of which the following, when taken in connection with the drawing accompanying and forming a part hereof, is a full and complete 10 description, sufficient to enable those skilled in the art to which it pertains to understand, make, and use the same.

This invention relates to latches which are used principally on vehicle doors, particularly on automobiles.

The objects of the invention are to obtain a device which can be used as a right hand or a left hand latch, a device which may be used with a knob, or with a lever, to operate 20 it; and a device which may be used with a lever only.

Further objects are to obtain a device which is not expensive to make, which is simple in construction, durable, and not 25 liable to get out of order.

In the drawing Figure 1 is a front elevation of a device embodying the principal features of the invention. Fig. 2 is a section, on line 2—2 of Fig. 1, viewed in the direction 30 indicated by the arrows. Fig. 3 is a perspective of the longitudinally movable bolt of the device which is illustrated in Figs. 1 and 2. Fig. 4 is a perspective view of one part of the two part casing of the device. 35 Fig. 5 is a front elevation of a device embodying the invention, with one part of the casing and the knob or handle of the casing removed, to expose the working parts to view. Fig. 6 is a perspective of the part of 40 the casing which is removed in Fig. 5. Fig. 7 is a perspective of the latch shown in Fig. 5. And Fig. 8 is an elevation of the lever of the device.

A reference letter applied to designate a 45 given part is used to indicate said part throughout the several figures of the drawing.

A is the shell or casing of the device, and 50 comprises part *a*, *a'* and rivet *a''*.

B is the latch of the device. The width of 55 latch B, (on line *b* of Fig. 3) is slightly less than the distance between the sides of part *a'* of casing A, so that said latch may move freely, longitudinally, in said part *a'*. Said part *a'* as thus constructed forms the guide

to latch B, as well as a cover holding said latch in place.

Part *a'* of the casing A is provided with the aperture C (Fig. 4) through which rivet *a''* extends when the parts *a*, *a'* are assembled, and the part *a* of the case is provided with a like aperture C', (Fig. 5) for said rivet. Part *a'* is also provided with the recesses D, D', to admit of the insertion therethrough of the lever J, hereinafter described. Said part *a'* is also provided with lugs E, E', which fit into corresponding apertures in the upturned end *a'''* of the part *a* of the casing A. Part *a'* is also provided with recess F to permit the retraction 60 of latch B, by the admission of part G of said latch in said recess. Latch B is provided with the lugs H, H'.

I is a spring yieldingly holding the latch B in an advanced position.

J is a lever which is fulcrumed on screw K.

k, *k'* are screw threaded apertures in part *a* of the casing A. The screw threaded part of the bolt K fits the screw threads of apertures *k* and *k'*, and the said bolt is screwed 80 tightly into the one of said apertures which is required to make a right or left hand latch, as desired, as will be hereinafter more fully set forth. Lever J is provided with the turned end *j*, at the free end thereof, and 85 portions are removed therefrom, as indicated by the curved lines L, L', near the fulcrumed end thereof. In addition to the change in position of the lever J which is permitted by the apertures *k*, *k'*, it may be 90 turned so that the bend at the free end thereof is as indicated by the broken lines *j'* in Fig. 2, when inserted in position in the casing A, instead of as is shown by full lines in 95 said figure.

When it is desired to construct the device so that the latch may be retracted by a knob as well as by movement of lever J, the latch B is provided with an aperture N and with shoulders P, P', and the parts *a*, *a'* are respectively provided with apertures in which the rocking part Q is journaled. The aperture in which rocking part Q is journaled in part *a'* of the casing is lettered O in Fig. 7, and the corresponding aperture in part *a* 100 of the casing is opposite thereto when the device is assembled.

R represents a square spindle which passes through a corresponding aperture in rock- 105 ing part Q.

The retraction of a latch by means of providing shoulders thereon corresponding to shoulders P, P', a rocking part Q engageable therewith, a square spindle and a knob 5 on said spindle is common to latches of this description.

To assemble the device the latch B is placed on the part a of casing A, part Q, where used, is put in place as illustrated in 10 Fig. 5, and the spring I is mounted on rivet a'', (said rivet having previously been secured in part a), and the part a' is secured in place by inserting the lugs E, E', in the apertures therefor in the turned up end of 15 part a and riveting the end of rivet a'' in hole C. The lever J is then put through the recesses D, D', in the sides of part a' of the casing, and between the latch B and part a of said casing. Bolt K is then screwed into 20 aperture k or k', as required, to form the fulcrum of said lever J. When thus assembled the spring I yieldingly holds the latch B in the position in which it is illustrated in Figs. 1 and 5, with lug H' on said 25 latch pressing against said lever J, so that no rattling of said latch or lever will occur. The cutting away of a portion of the said lever J, as indicated by lines L is to prevent 30 said lever from coming in contact with lug H when the latch B is advanced, or with the end of recess D, at said time.

To operate the latch, that is to retract the latch against the resiliency of the spring I, it is simply necessary to move lever J from the 35 position which is illustrated in full lines in Fig. 1, to the position which is indicated by broken lines in said figure. Upon releasing

the lever J the spring I will return said lever and latch B to the position in which they are shown in said Fig. 1.

The rocking part Q forms a right and left hand latch of the device when a handle or knob is mounted on the square spindle R; and the lever J makes a right or left hand latch of the device according to whether it 45 is inserted first in recess D, or in recess D'; (that is, whether the bolt K is screwed into aperture k or k').

I claim;—

In a latch comprising a casing provided with slots on the upper and lower sides thereof, a longitudinally movable bolt provided with lugs positioned adjacent to said slots, and a spring adapted to advance said bolt and yieldingly hold it in an advanced 50 position, the combination of a fulcrum attachable to said casing in a plurality of positions and a lever mounted on said fulcrum to extend through said slots, said lever provided with recesses positioned on its edges, 55 near said fulcrumed end and in said lower slot to prevent said lever coming in contact with the forward end of said lower slot, to prevent said lug which is adjacent to said lower slot coming in contact with said lever, 60 to permit said lever to come in contact with the forward end of said upper slot and to permit said lug which is adjacent to said upper slot to come in contact with said lever.

WILLIAM H. APPLEBY.

In the presence of—

JOHN G. GILL,

CHARLES TURNER BROWN.
